UNITED STATES PATENT OFFICE.

JOHN F. PRICE, OF PITTSBURGH, PENNSYLVANIA, ASSIGNOR TO THE McCONWAY & TORLEY COMPANY, OF PITTSBURGH, PENNSYLVANIA, A CORPORATION OF PENNSYLVANIA.

DRAFT APPLIANCE FOR RAILWAY-VEHICLES.

1,164,209.

Specification of Letters Patent. Patented Dec. 14, 1915.

Application filed July 17, 1915. Serial No. 40,371.

To all whom it may concern:

Be it known that I, JOHN F. PRICE, a citizen of the United States, residing at Pittsburgh, in the county of Allegheny and State of Pennsylvania, have invented certain new and useful Improvements in Draft Appliances for Railway-Vehicles; and I do hereby declare the following to be a full, clear, and exact description of the invention, such as will enable others skilled in the art to which it appertains to make and use the same.

My invention relates to the construction of draft appliances for railway vehicles, and particularly to means for permitting the coupler to yield laterally when the car to which it is attached moves upon curved track and for automatically restoring the coupler to normal position in the longitudinal axis of the car upon the cessation of the force causing the lateral displacement of the coupler.

The principal object of the invention is to provide a simple, durable, and efficient coupler centering mechanism which may be readily assembled and repaired without the necessity of employing special tools for that purpose. Generally stated, this object is accomplished by pivotally mounting the coupler head upon the coupler stem and by slidably mounting on said stem a frame which engages the head, said frame having mounted upon it means for centralizing the coupler stem and being yieldingly supported against rearward movement by a longitudinally extending spring which is seated on the stem, and such frame involving in its construction interfitting counterpart members which are provided with lugs that project laterally outward and also involving a transversely extending member that engages the forward sides of said lugs and connects said counterpart members.

In the drawings illustrating the preferred form of my invention, the scope whereof is pointed out in the claims, Figure 1 is a plan view of a draft appliance embodying my invention, a portion of the stem of the coupler being broken away and a portion of the coupler head being shown in horizontal section. Fig. 2 is a side elevation of the mechanism shown in Fig. 1. Fig. 3 is a vertical longitudinal section of the forward portion of the mechanism illustrated in Figs. 1 and 2. Fig. 4 is a vertical section, taken in the

plane of the line 4—4, Fig. 1. Fig. 5 is a rear elevation of the transversely extending, spring-seat member of the frame; and Fig. 6 is a perspective view of one of the counterpart members of the slideable frame.

In the drawings, 1 indicates the coupler head and 2 indicates the coupler stem. These parts are pivotally connected by means of a bolt or pivot pin 3 which extends vertically through corresponding openings 4 and 5 in the coupler head and at the forward end of the coupler stem, respectively.

The coupler stem 2 is preferably of bifurcated form, having upper and lower branches or bars 6 between which is mounted the slideable frame that carries the laterally projecting spring-supported followers 7 by which the centralization of the coupler as a whole is effected. At its rear end the coupler stem is preferably provided with a vertically extending opening 8 which is adapted to receive the usual tail-pin (not shown) whereby the coupler may be pivotally connected to the car or other railway vehicle through the medium of yielding draft rigging mechanism. A filler or spacing member 9 which is interposed between the branches 6 of the stem and which is preferably secured thereto by means of a rivet 10 may be conveniently employed as a seat for the rear end of the longitudinally extending spring 11 by which the slideable frame is resiliently supported.

The spring cups or followers 7 which are mounted upon the reciprocating frame respectively project outwardly beyond the sides of the coupler stem 2 in opposite directions and normally engage stationary abutments 12 upon the car, as shown in Fig. 1. Interposed between these spring-cups and bearing upon each is a transversely extending spring 13 which serves to normally maintain said spring-cups in a position of maximum separation. The extent of separation of the spring-cups or followers 7 is preferably limited by forming the inner end of each spring-cup with flanges 14 which are adapted to engage the inner walls or stops 15 of the slideable frame adjacent to the openings 16 in said frame through which the respective spring-cups 7 project. If desired, a pin or bar 17, which is loosely inserted within the spring 13, may be employed to prevent such spring from being

compressed to such an extent as would be liable to damage it. The spring-cups 7 and the transversely extending spring 13 co-operate with the slidable frame to centralize the coupler stem 2, as well as the coupler as a whole, as will hereinafter appear.

The slidable frame upon which the followers or spring-cups 7 are mounted involves longitudinally extending separable members 18, 18 and a transversely extending member 19 by which the longitudinally extending frame members are connected transversely. The members 18 are preferably counterparts and the transversely extending frame member 19 preferably forms a seat upon which the forward end of the longitudinally extending spring 11 bears. To maintain the spring 11 in assembled relation with the slidable frame, the rear face of the frame member 19 may be provided with a centrally disposed, rearwardly extending projection or thimble 20 which is adapted to enter the interior of the spring. At their forward ends each of the counterpart members 18 is preferably fashioned with a transversely extending projection 21 that may be formed with a hole or opening 22 which is adapted to receive a transversely extending bolt 23 that may be conveniently employed as a means for preventing the lateral separation of the forward ends of the counterpart members 18. The projections 21 preferably have interfitting engagement with each other when the parts are in assembled relation, the engagement of the parts being of a character to cause both of the counterpart frame members to reciprocate in unison on the coupler stem as if they were a unitary member. To this end each of the projections 21 may be provided with a laterally extending, preferably tapering locking lug 24 with a recess 25 of similar form, the lug 24 and recess 25 being arranged in vertical alinement and on opposite sides of the hole 22 through which the bolt 23 passes. The vertically extending faces 26 at the bases of the respective projections 24 are adapted to abut each other to thus maintain the forward ends of the counterpart members 18 in proper spaced relation. When assembled each lug 24 enters the corresponding recess 25 in the opposite counterpart member 18.

Near its rear end each of the frame members 18 is preferably provided with an inwardly extending projection 27. The inner ends of these projections stand opposite and are adapted to engage each other to maintain the counterpart members 18 in proper relation at their rear ends. To prevent the lateral displacement of the slidable frame with respect to the stem 2 of the coupler upon which it is mounted, the side walls of each of the counterpart frame members 18 are preferably extended vertically suffi-

ciently far, as at 28, to have overlapping engagement with the lateral edges of the branches or plates 6 of the coupler stem. If a transversely extending bolt 23, or the like, is employed as a means for connecting the forward ends of the frame member 18, the outer faces of said members are preferably respectively fashioned with recesses or countersinks 29 to receive the bolt head and nut.

At its rear end each of the counterpart members 18 is provided with a lug 30 which projects laterally outward. As shown more particularly in Figs. 1 and 6, these lugs 30 are preferably fashioned with curved, vertically extending faces which are adapted to be received in curved seats 31 with which the transversely extending frame member 19 is provided on its forward face. The curved seats 31 of the frame member 19 are preferably formed by fashioning this spring-seat member with a plurality of hooks, there being one hook at each end. The hook portions of the spring seats 19, respectively overlap the projecting lugs 30 of the counterpart members 18 and engage the forward sides of said lugs, thus connecting said counterpart members against lateral separation.

The coupler head 1 is provided with a rearwardly opening tapering pocket 32 into which the forward ends 33 of the counterpart members 18 extend, the coupler head being provided with laterally extending vertical shoulders 34 against which the outer extremities of the members 18 bear when the coupler head occupies its normal position with respect to the coupler stem 2. The contracting pocket 32 of the coupler head into which the counterpart members 18 extend thus assists in preventing the outer ends of the frame members 18 from separating.

The mechanism may be assembled by positioning the spring 11 between the branches 6 of the coupler stem 2 and then bringing the frame member or spring seat 19 into proper relation with the forward end of said spring. The spring cups or followers 7 are then inserted through the appropriate openings 16 of the frame members 18 and the transversely extending spring 13 and the stop pin 17 within said spring are placed in position. The forward ends of the counterpart frame members 18 being separated somewhat, the lugs 30 at the rear ends of said members are inserted in the curved seats 31 at the outer ends of the frame member 19 and the forward ends of the frame members 18 are then brought together until the projections 21 on said frame members last mentioned come into interfitting engagement. The bolt 23 may be then passed through the counterpart members 18 and the nut applied thereto. The coupler head 1 is then associated with the

coupler stem 2 and the pivot pin 3 which connects the head and stem is inserted.

The operation of the mechanism is as follows: When the car or other railway vehicle 5 to which the mechanism is applied moves upon curved track the force applied to the coupler head causes the coupler to be displaced laterally from its normal position in the longitudinal axis of the car. As the 10 stem 2 of the coupler moves sidewise it carries with it one of the followers or spring-cups 7, being enabled so to do because of the engagement of the slideable frame with the flanges 14 at the base of the spring-cup. 15 During this movement the other follower or spring-cup 7 is prevented from retreating since it engages a stationary abutment 12 upon the railway vehicle. The spring-cups 7 thus approach each other and the trans- 20 versely extending spring 13 which is inter- posed between them is, therefore, com- pressed. Upon the expansion of the spring 13 the resultant outward movement of the follower 7 which has been displaced from 25 normal position, acting through the slideable frame, causes the coupler stem 2 to be re- stored to its normal position in the longitu- dinal axis of the car. When the coupler head 1 rotates with respect to the coupler 30 stem, one or the other of the transversely extending vertical shoulders 34 of said head bears against the forward end 33 of the ad- jacent counterpart frame member 18, thus 35 causing the entire frame to slide rearwardly upon the coupler stem. This compresses the longitudinally extending spring 11, which is seated upon the transversely extending spring-seat 19 forming the rear end of the frame. When the force causing the dis- 40 placement of the coupler head 1 ceases to act, the spring 11 is permitted to expand. This restores the slideable frame to its normal position and returns the coupler head 1 to a centralized position with respect to the cou- 45 pler stem. The described movements of the coupler stem and of the coupler head with respect to the stem usually occur simultaneously, as will be readily appreciated.

I claim:

50 1. The combination with a car coupler having a stem and a head pivotally mounted thereon, of a frame engaging said head and slideably mounted on said stem, means carried by said frame for centralizing said stem, and a spring yieldingly supporting said frame, said frame involving separable members having engaging parts, and detachable means for connecting said separable members laterally, said detachable means 55 being provided with a plurality of hocks which respectively engage the said separable frame members.

2. The combination with a car coupler having a stem and a head pivotally mounted thereon, of a frame engaging said head and slideably mounted on said stem, means carried by said frame for centralizing said stem, and a spring operatively interposed between said frame and stem, said frame involving counterpart members having inter- 65 fitting portions and a member having curved seats which are adapted to respectively re- ceive the rear ends of said counterpart mem- bers.

3. The combination with a car coupler 75 having a stem and a head pivotally mounted thereon, of a frame engaging said head and slideably mounted on said stem, means carried by said frame for centralizing said stem, and a spring operatively interposed 80 between said frame and stem and extending in the direction of length of said stem, said frame involving counterpart members hav- ing interfitting engagement at their forward ends and respectively provided at their rear 85 ends with lugs which project laterally out- ward, and said frame also involving a mem- ber engaging the forward sides of said lugs and connecting said counterpart members.

4. The combination with a car coupler 90 having a stem and a head pivotally mounted thereon, of a frame engaging said head and slideably mounted on said stem, a longitudinally extending spring interposed between said frame and said stem, followers carried 95 by said frame and projecting laterally there- through, and a transversely arranged spring interposed between said followers, said frame involving counterpart members hav- ing interfitting portions, each of said coun- 100 terpart members having an aperture adapt- ed to receive one of said followers and hav- ing an outwardly projecting lug at one end, and said frame also involving a transversely extending member having curved seats 105 which are adapted to respectively receive said lugs.

5. The combination with a car coupler having a stem and a head pivotally mounted thereon, a frame slideably mounted on said stem and engaging said head, a spring operatively interposed between said frame and stem, and means carried by said frame for centralizing said stem, said frame involving separable members which engage said coupler head, a transversely extending member provided with hooked portions having over- 115 lapping engagement with each of said sepa- rable frame members, at one end thereof, and transversely extending means passing 120 through said separable frame members and connecting the same.

In testimony whereof I affix my signature.
JOHN F. PRICE.
